UNITED STATES PATENT OFFICE.

STEPHEN G. CLAYBACK, OF GARDENVILLE, NEW YORK.

AIR-BRAKE-PISTON-LEATHER-EXPANDING RING.

1,393,664.

Specification of Letters Patent. Patented Oct. 11, 1921.

Application filed October 22, 1919. Serial No. 332,516.

To all whom it may concern:

Be it known that I, STEPHEN G. CLAYBACK, a citizen of the United States of America, residing at Gardenville, in the county 5 of Erie and State of New York, have invented certain new and useful Improvements in Air-Brake-Piston-Leather-Expanding Rings, of which the following is a specification.

10 The primary object of the invention is the provision of an expanding ring for the piston leather of an air brake cylinder that is simple in construction, easy and inexpensive to manufacture adapted to maintain the 15 leather against the walls of the air brake cylinder when the device is in use.

My invention is beneficial to the public safety in perfecting the air brake equipment of railway cars and includes a ring preferably stamped from sheet metal and having a stiffening portion for attaching the ring to the piston and follower and also having freely expanding tongues constantly pressing the leather against the walls of the cylinder and avoiding all leakage when the expanding ring is in use.

A further object of the invention is to provide an expanding ring without joints adapted for preventing any kinks or unevenness in the piston leather, the device being entirely automatic after installation in maintaining the piston air-tight during operation.

With these general objects in view, the 35 invention consists of the novel combination and arrangement of parts hereinafter more fully described in connection with the accompanying drawing and in which like reference characters designate corresponding parts throughout the several views.

In the drawing,

Figure 1 is a sheet metal blank or plate preferably formed by a stamping press,

Fig. 2 is an elevational view of the expanding ring in its finished condition, and

Fig. 3 is a diametrical sectional view thereof taken upon line III-III of Fig. 2.

It being understood that my invention broadly contemplates the provision of a ring 50 for expanding the leather packing ring of an air brake piston, I have illustrated an annulus 10 of sheet metal in Fig. 1 of the drawing formed by a stamping press. The blanking press is then employed for stamping

equally spaced radial fingers 11 in the outer 55 periphery of the blank 10, these fingers being heated and bent upwardly at an angle of 45° to the body portion 12 of the blank as illustrated in Figs. 2 and 3.

The inner margin of the body portion 12 60 is folded outwardly upon itself to provide an annular bead 13 which imparts proper stiffness to the packing expanding ring. It will be understood that the body portion 12 of my packing expanding ring herein described is adapted for seating upon the leather packing ring with the packing ring seated upon the annular seat of the piston, a plurality of nuts or stud bolts being employed for securing the follower upon the 70 piston seat over the expanding ring.

The complete operation of the invention will be fully understood from this detail description thereof, the fingers 11 being resilient constantly bear against the leather packing ring maintaining the leather in flat resilient contact against the inner wall of the air brake cylinder, thereby avoiding kinks or wrinkles in the leather and rendering the piston leak-tight. The fingers 11 are 80 free to expand during the operation of the piston and the leather packing ring is maintained air-tight in the cylinder although the piston may be slightly out of true or wobble during the reciprocations of the piston. The 85 scallops or excisions 14 between the fingers 11 extend inwardly toward the axial center of the expanding ring substantially to the outer periphery of the clenched over stiffening bead 13, the bends 15 of said fingers 11 90 being intermediate the ends of the fingers and closer to the bead 13 than to the extremities of the fingers. This affords greater elasticity in holding the piston leather in air-tight position for use.

95 While the form of the invention herein set forth is believed to be the preferable embodiment thereof, it is to be understood that minor changes may be made therein without departing from the spirit and scope of the 100 invention.

What I claim as new is:—

A ring for expanding the piston leathers of an air brake cylinder formed from an annular sheet metal blank, the inner margin 105 of said blank bent outwardly upon itself forming a stiffening portion having flat engaging faces for attaching the ring to the

receiving seat of a piston, the outer periphery of the blank being scalloped forming spaced radial fingers bent upwardly in a uniform direction throughout the circumference of the blank at points adjacent the stiffening portion to provide relatively long fingers adapted for resilient bearing upon

the piston leather to maintain the latter at all times against leakage and against the wall of the cylinder during the operation of the piston.

In testimony whereof I affix my signature.

STEPHEN G. CLAYBACK.
